UNITED STATES PATENT OFFICE.

ERNEST L. WETZIG, OF JUNCTION CITY, KANSAS.

APPARATUS FOR RESIZING, DECAPPING, AND RECAPPING CARTRIDGE-SHELLS.

SPECIFICATION forming part of Letters Patent No. 742,768, dated October 27, 1903.

Application filed December 13, 1902. Serial No. 135,062. (No model.)

To all whom it may concern:

Be it known that I, ERNEST L. WETZIG, a citizen of the United States, and a resident of Junction City, in the county of Geary and State of Kansas, have made certain new and useful Improvements in Apparatus for Resizing, Decapping, and Recapping Cartridge-Shells, of which the following is a specification.

It is well known to those acquainted with the use of breech-loading shotguns that after shells have once been fired they are not of the same size, since some guns have a larger breech-chamber than others, and hence a shell which does not fit the same when shot therein will expand to the size of the chamber. It is impossible to reuse such a shell in a gun having a smaller chamber. It is also often desirable to re-form or reshape shells which have been once used in order to adapt them for reuse in the same gun in which they were discharged.

My improved apparatus comprises fixed parts adapted to be secured to a wall or other fixed support and other parts adapted to slide on or in such parts, whereby shells may be resized and also decapped and recapped by a simple manipulation of parts.

The details of construction, arrangement, and combination of parts are as hereinafter described, reference being had to the accompanying drawings, in which—

Figure 1 is mainly a front view of the apparatus, the lever being broken away and certain portions being shown in section, illustrating the operation of resizing a shell. Fig. 2 is mainly a vertical section of the apparatus, a portion being shown in side view and the lever being shown by dotted lines illustrating the operation of forcing a shell out of the resizing-die and decapping same. Fig. 3 is a horizontal section on the line 3-3 of Fig. 1. Fig. 4 is a perspective view of the apparatus, minus a portion of the lever, the same illustrating the position of parts when a shell is decapped and forced out of the resizing-die. Fig. 5 is a perspective view of a slidable portion of the apparatus. Fig. 6 is mainly a sectional elevation and in part a side view of the apparatus, illustrating the operation of recapping a shell. Fig. 7 is a perspective

view of a plug which is employed in recapping shells.

In the following description and in the drawings the fixed portions of the frame will be designated by letters, and the parts of the apparatus which are movable in the several portions are designated by numerals.

Referring especially to Figs. 1 and 4, A, B, and C indicate horizontal blocks or brackets, which are arranged in vertical alinement and secured by screws to a wall or other fixed vertical support. Rods D are arranged in holes in the several brackets and secured detachably therein by means of clamp-screws a. The above parts constitute the fixed portion or frame of the apparatus.

The rods D serve as guideways for a transverse cross-head 1, (see Fig. 5,) to which vertical rods 2 are detachably secured by means of clamp-screws 3. This cross-head 1 is arranged between the two brackets B and C. A tubular and flanged resizing-die 4 is arranged and supported in a central opening in the intermediate bracket B, the same being secured detachably by means of a clamp-screw 5. A plunger 6 passes through a central opening in the lower bracket C, also through an opening in the sliding cross-head 1 and through the resizing-die 4, there being sufficient space between it and the die for reception of the body of the cartridge-shell x, as shown in Figs. 1, 2, and 6. This plunger 6 is provided at one end with a central pin 6^a. (See Figs. 1, 2, and 4.) The opposite end (see Figs. 1 and 6) is provided with a recess or socket 6^b. The plunger 6 is adapted to be reversed end for end, according to the function it is to perform, as will be presently explained. These slidable rods 2, connected with the cross-head 1, are provided with cross-pins 7. (See Figs. 1, 4, and 5.) In the space between the said cross-pins is arranged a cross-bar 8, which is slidably mounted on rods 2, and the same is connected by links 9 with a lever 10. The latter is pivoted at 11 (see especially Figs. 2 and 4) to the bracket A, and the end of the lever, whose body is formed with two parts, is provided with a handle, as indicated by dotted lines in Fig. 2, for convenience and ease of manipulation of the same. It is apparent that the lever 9 swings in a vertical

plane and that when the lever is thus operated the cross-bar 8 is caused to slide up and down correspondingly, it being guided on the rods 2 and the latter being raised or forced 5 down, according as the bar 8 strikes upon the upper or lower set of cross-pins 7.

When it is desired to resize shells that have been used, the plunger 6 is clamped in cross-head 1 by means of the screw 12, and the screw *b* of the lower bracket C is adjusted 10 out of contact with the plunger, so that the latter is left free to slide in said bracket and may be also slid down through the resizing-die 4 to the position indicated in Fig. 1. The cross- 15 bar or pusher 8 is then pushed down until it forces the shell into the die and between it and the plunger. Thus the shell will be resized as required. Then upon raising the lever 10 the bar 8 will be slid upward into contact with the upper pin 7, and thus the rods 2 will be drawn upward, carrying with them the cross-head 1 and plunger 6, since the latter is clamped to the cross-head by the screw 12. The upward motion of the lever being 20 continued far enough, the plunger 6 will be raised, as indicated in Figs. 2 and 4, and the pin 6^a coming in contact with the exploded cap or primer the latter will be forced out of the shell, and the latter will be lifted bodily 25 out of the resizing-die. It will be seen, therefore, that by pressing the lever 10 down a shell is resized, and when the lever is raised the shell is decapped and removed.

In order to cap a shell, the plug 13 (see 30 Figs. 6 and 7) is inserted and held in vertical position in the cross-bar 8 and clamped by the screw 14. The plunger 6 is also reversed end for end, so that the pin 6^a is downward and the socket 6^b is uppermost. The screw 40 12 in cross-head 1 is also secured out of engagement with the plunger, and the screw *b* of the lower bracket C is screwed into engagement with the same, as shown in Fig. 6. Thus the plunger is held fixed in the lower 45 bracket C, while the cross-head 1 is free to slide thereon. A shell cap or primer *y* being then placed on the head of the shell *x* and the plug 13 forced down by proper manipulation of the lever 10 the shell will be 50 duly recapped. Thus the apparatus is adapted for recapping shells by simply reversing the position of the plunger 6, adjusting the screws 12 and *b*, and setting the plug 13 in the cross-bar 8. It is necessary to set the 55 plunger 6 high enough to support the shell *x* above the die 4, since if the shell were forced into the die it would be difficult to remove it.

The pin 6^a of the plunger is made detachable, so that pins of different lengths may be 60 employed as conditions require. It is also apparent that by means of the clamp-screws 12 of the cross-head 1 and *b* of the bracket C the plunger may be set higher or lower, according to the thickness of the head of the shell. The resizing-die may be readily removed, if it be desired to substitute another 65 of slightly-different diameter.

The apparatus is very strong and durable and composed of few parts, which are adapted to be readily detached, if required, for 70 packing in small space for shipment or storage.

Having thus described my invention, what I claim as new, and desire to secure by Letters Patent, is—

1. The combination, with three brackets arranged in vertical alinement and vertical guides held therein, a cross-head slidable on said guides, rods affixed to such cross-head and guided in the upper brackets and also 80 provided with stops, of a pivoted lever and a cross-bar connected therewith and sliding on the slidable rods between the stops thereof, a resizing-die held in the intermediate bracket, and a plunger secured in the slidable cross- 85 head and adapted to work through the resizing-die, said plunger being provided with a pin for decapping shells, substantially as shown and described.

2. The combination, with three alined 90 brackets adapted to be secured to a fixed support, a shell-resizing die held in the middle bracket and guide-rods held in said brackets, of a cross-head adapted to slide on the guides and having rods attached to it which 95 slide in the two upper brackets, and are provided with stop-pins, a cross-bar adapted to slide on such slidable rods between the stop-pins to force a shell into the die, and a lever pivoted to the upper bracket and connected 100 with the slidable cross-bar, all operating as shown and described.

3. The combination, with three alined brackets adapted to be secured to a fixed support, a shell-supporting device held in the 105 middle bracket, guides held in said brackets, a cross-head slidable on the guides and having rods connected therewith and sliding in the upper brackets, and provided with stops, a plunger carried by the cross-head and working through the shell-support, the same being provided at its upper end with a projecting pin, a lever pivoted to the upper bracket, a cross-bar which is slidable on the slidable rods between the stops thereon and links connecting such cross-bar with the lever, whereby, when the latter is vibrated in a vertical plane, the cross-bar is alternately forced down and up, as required to force the shell into the support and to decap the same, substantially as shown and described.

4. The combination, with three brackets adapted to be attached to a suitable support, and a resizing-die held in one of said brackets, of a slidable cross-head and rods affixed thereto and sliding in the two upper brackets, a cross-bar which is slidable on the slidable rods, a plug secured in such cross-bar for use in recapping shells, a lever and links for moving the cross-bar on the slidable rods, and a plunger held in the lower bracket and projecting into the resizing-die, substantially as shown and described.

5. The combination, with three brackets

adapted to be secured to a suitable support, and guide-rods held therein, of a cross-head adapted to slide on the guides between the lowermost and intermediate brackets, rods fixed to the cross-head and sliding through the intermediate and upper brackets and provided with stops, a cross-bar which slides on the slidable rods and is provided centrally with an opening and clamp-screw for receiving and securing a plug adapted for use in recapping shells, a pivoted lever connected with such cross-bar for shifting it on said slidable rods between the stops thereof, and a plunger which is adapted to be reversed end for end, it being provided at one end 15 with a projecting pin and at the other end with a socket, and means for securing it in the lower bracket or in the cross-head, as conditions require, substantially as shown and described.
